UNITED STATES PATENT OFFICE.

JOSEPH MEINECKE, OF PAIA, MAUI, TERRITORY OF HAWAII.

ROTARY CUTTER FOR SUGAR-CANE AND THE LIKE.

1,217,326.

Specification of Letters Patent. Patented Feb. 27, 1917.

Application filed May 13, 1916. Serial No. 97,319.

To all whom it may concern:

Be it known that I, JOSEPH MEINECKE, a citizen of the United States, residing at Paia, Maui, Territory of Hawaii, have invented certain new and useful Improvements in Rotary Cutters for Sugar-Cane and the like; and I do hereby declare the following to be a full, clear, and exact description of the invention, such as will enable others skilled in the art to which it appertains to make and use the same.

This invention relates to rotary cutters, such as used for cutting and shredding sugar-cane and the like, and has for its object to provide an improved cutter of this type which is so constructed that it will more efficiently cut or shred the sugar-cane or other material operated upon than cutters of the type heretofore employed.

39. The invention is illustrated in the accompanying drawing, in which:

Figure 1 is a side elevation of the improved cutter;

Fig. 2 is an edge view of the cutter with the hub represented in section; and

Fig. 3 is an enlarged edge view, partly in section, more clearly illustrating the shape of the knife-blade seats and their effect in causing the extremities of the knife-blades 40 to assume an offset relation with respect to each other and with respect to the longitudinal axis of the hub.

The improved cutter comprises in its preferred form, a hub 1 having a central opening which adapts the hub for use on a cutter shaft, such as shown at 2. The hub may be secured to the shaft in any suitable manner, such as by means of the key 3.

The hub 1 carries a plurality of knife-blades having the general shape and construction clearly shown in Fig. 1. Any suitable number of these blades may be employed, but preferably there are four of the same, two diametrically opposite blades 4 and 4' being secured to one cheek 5 of the hub, and the other two diametrically opposite blades 6 and 6' being secured to the opposite cheek 7 of the hub. The knives may be secured to the hub by any appropriate means, such as the bolts 8. The provision of four knife-blades and the mounting of the two pairs of blades on opposite cheeks of the hub result in a well-balanced cutter, but as will later be seen, these features of construction need not be adhered to, as the cutter

may be constructed in various other ways without departing from the spirit of the invention.

The main feature of construction which distinguishes the present cutter from other cutters of the same general type is that all of the cutters carried by the hub 1 are so disposed that their extremities will be in spaced relation, or, in other words, assume an offset relation with respect to each other and with respect to the longitudinal axis of the hub. Otherwise stated, the extremities of the knife-blades will lie in different planes passing through the axis of the hub. This is accomplished in the present instance by mounting the knife-blades in seats provided in the hub cheeks and so shaping all of said seats that the longitudinal axes of the blades will be so disposed with respect to the axis of the hub that the extremities of the blades will assume the relation above indicated. For instance, the blades 6 and 6' are mounted in seats 9 and 10, respectively, the bottom surface of the seat 9 being substantially at right angles to the axis of the hub, 80 so that the blade 6 also assumes a position at right angles to the axis of the hub and the seat 10 being so shaped that its bottom surface will be slightly inclined with respect to the axis of the hub. This will result in an 85 inclination of the longitudinal axis of the blade 6', as indicated in Figs. 2 and 3, so that the extremities of the blades of the pair 6, 6' will fall in different planes or be spaced from each other longitudinally of 90 the hub axis, as clearly indicated in Fig. 3. Likewise, the blades 4 and 4' are mounted in seats 11 and 12, respectively, the seat 11 having its bottom surface inclined with respect to the axis of the hub to cause the 95 knife-blade 4 to assume the position indicated in Fig. 3, thereby bringing its extremity into the proper spaced relation with respect to the extremity of the blade 6. The seat 12 has its bottom surface at right angles to the axis of the hub, so that the blade 4' will also be at right angles to the axis of the hub and so that the extremity of the blade 4' will assume the proper spaced relation with respect to the extremity of the 100 blade 4. The result of the formation of the seats in this manner is shown in Fig. 3, from which it will be noted that the longitudinal axis of each blade is so disposed with respect to the axis of the hub that the ex- 110

tremities of the knives lie in different planes and are in spaced relation longitudinally of the hub axis.

In practice, it is customary to mount a plurality of the hubs upon a single cutter shaft and, when a plurality of the present hubs are so positioned upon a single shaft, it is obvious that the extremities of all of the blades of all of the hubs may be made to 10 lie in different planes and be in spaced relation, the spacing between the extremities of the blades being the same throughout the length of the shaft when the hubs are properly spaced on the shaft to bring about this 15 result. It will now be noted that the four blades carried by any one hub are capable of producing four successive cuts upon different portions of the material treated. The result is that the material is cut or shredded 20 in a much more efficient manner than has been possible with cutters as heretofore constructed. When the cutters are employed for cutting or shredding sugar-cane, it has been found desirable in practice to so dis-

pose the knife-blades as to bring their extremities in planes which are substantially seven-eighths of an inch apart.

The means herein disclosed for bringing the extremities of all of the blades carried by one hub into spaced relation is only one of a number of ways in which this result might be obtained, and, therefore, I do not wish to limit myself to the specific means herein shown and described.

What I claim is:—

A rotary cutter comprising a hub having a pair of cheeks, each provided with a pair of knife-blade seats, and a knife-blade mounted on each of said seats, one of the seats of each pair being in a plane at right angles to the hub axis and the other seat of each pair being in a plane which is inclined with respect to the hub axis to bring the extremities of the blades into spaced relation longitudinally of the hub axis.

In testimony whereof I affix my signature.

JOSEPH MEINECKE.
